UNITED STATES PATENT OFFICE.

WILLIAM P. QUENTELL, OF NEW YORK, N. Y.

TYPE-WRITING MACHINE.

SPECIFICATION forming part of Letters Patent No. 624,865, dated May 9, 1899.

Application filed July 15, 1898. Serial No. 686,031. (No model.)

To all whom it may concern:

Be it known that I, WILLIAM P. QUENTELL, a citizen of the United States, residing at New York, in the county and State of New York, 5 have invented new and useful Improvements in Type-Writing Machines, of which the following is a specification.

By means of this invention a type-writing machine can be obtained which is cheap and 10 simple of construction, as set forth in the following specification and claims and illustrated in the annexed drawings, in which—

Figure 1 is a plan view of the machine with parts broken. Fig. 2 is a sectional side elevation of Fig. 1. Fig. 3 is a view similar to Fig. 2 on a larger scale. Fig. 4 is a plan view showing the type-segment as having been moved. Fig. 5 is a detail view of part of a key-lever. Fig. 6 is a detail view of part of 20 the cross-bar which actuates the hammer-actuating lever and the spacing mechanism.

On a suitable base 1 is a track or way 2, Fig. 3, for the paper-carriage 3, having feed-rollers 4 and 5 for the sheet or paper coming 25 from the storage 6. The sheet passing back of type wheel or segment 7 receives a print when driven against the type by the stroke of hammer 8, Fig. 2, having its fulcrum or support at 9. A stud 10 on the hammer is engaged by arm 11 of lever 11 12, fulcrumed at 13 and having cross-bar 14. The key-levers 15, fulcrumed at 16, Fig. 3, engage or rest on the cross-bar 14 and are provided with finger buttons or keys 17, as customary. When a 30 key-lever is depressed, it acts on cross-bar 14 to swing lever 12 11 and cause arm 11 to swing the hammer 8 so as to make a stroke or print. This bar 14, as seen in Fig. 6, has a cut or depression 18, located centrally or at 35 40 the spacing-key 19, so that the latter is depressed or actuated without moving bar 14 or hammer 8. The bar 14 can be steadied by arms 20, Fig. 4, swinging on fulcrum 13 and forming, with bar 14, a bail-like structure.

The type-segment 7, with its shaft 21, is rotated or swung by the depression of a key, as 45 presently explained. A stop-arm 22 is fixed on or extends from this shaft. The keys have stop-pieces which, as seen in Fig. 5, comprise 50 each a stop portion 23 and a cut or passage portion 24. The cuts or recesses 24 allow the type stop-arm 22 to pass or swing by the re-

spective keys when the latter are at rest; but a depression or movement of the key brings the full or stop portion 23 into the path of 55 arm 22 to arrest the latter. The pieces 23 can be formed or cast integral with the key-levers or secured or jointed thereto in suitable way. The stop-pieces are shown extending upwardly from the key-levers, and a guide 60 or plate 25, having ways or perforations 26, is provided for the stop-pieces. This guide 25 is applied above the levers 15, and the type stop-arm 22 is made to travel between this plate 25 and the key-levers. 65

In Fig. 3 is shown in full lines a key 15, with stop-piece 23, at rest or in normal position, the passage or receding portion 24 of the stop-piece being in position for arm 22 to pass or travel by. In broken lines is shown a key 15 70 depressed, the corresponding stop-piece having brought its stop portion or full upper part 23 into the path of arm 22 to arrest the latter. 75

The type-segment 7 is loose on shaft 21, but is caused to rotate therewith by arm 27, Fig. 3, engaging the type-segment and extending from shoulder or transmission piece 28, Fig. 4, fixed to the shaft. The shaft is rotated one way or another, as the respective one of the 80 oppositely-located shoulders of piece 28 is actuated by its lever-arm 29. These levers 29 30 are fulcrumed at 31 and are each connected at 32, as by a pin or stud, to a lever 33, fulcrumed at 34. Each lever 33 is provided with 85 what may be called a "cross-piece" 35. As a key 15 at one side or another of the machine is actuated its respective lever 33 is actuated, together with the respective lever 29, so that the type-shaft is swung one way or another. 90

The cross-bars 35, it is noticed, do not extend at right angles to their respective key sets; but each bar is inclined or arranged so that at one end or portion it lies nearer to fulcrum 16 than at the other end or portion. 95 Say a key 15 is depressed, which acts on that portion of a bar 35 which is near to fulcrum 16. Then this bar 35, with its lever 33, is actuated to a certain extent, so as to move the type-segment 7 and bring a certain type to 100 the printing-point. When a key 15 is depressed which acts on that portion of a bar 35 which is farther from fulcrum-strip 16, the degree of play or depression of the various

- keys being the same or practically so, such depression of the last-named key will cause bar 35, with lever 33 and type-segment 7, to be actuated to a different extent and another 5 type to be brought to the printing-point. As the various keys are thus depressed and engage different points along one or another of the inclines 35 the type relating to the successively-actuated keys are brought to the 10 printing-point as required. As a key 15 actuates or depresses bar 14 the latter actuates the free or end portion 36, Fig. 4, of an arm 37, extending from rock-shaft 38, connecting by arm 39 and link 40 with arm 41 of feed-dog 42, Fig. 3, engaging rack 43 of carriage 3. As the dog 42 is thus oscillated or actuated under the influence of lever 37 38 39 and of returning-spring 44, the carriage is fed, as known.
- 20 At 45, Fig. 4, is shown fulcrumed an arm 46, the free or end part 47 of which engages arm 37 at some distance from its free end 36 or near to fulcrum 38. The spacer 19 engages arm 46, and as the latter is swung or depressed by the spacer the parts 37 38 39, with dog 42, are actuated.
- The type-segment may have different type rows brought into action by case or shift keys 48; but as such arrangements are known no 25 description thereof is here required.
- The hammer-actuating lever 11 12, it is found, is practically arranged so that the arm 11 directly or positively engages the hammer and does not carry the hammer all the way 30 to the printing-point; but said arm stopping short before the hammer reaches such point the latter, swinging loosely on pivot 9, will by its momentum continue to move until the print is made.
- 35 The type-segment shaft 21, the keys 15, and the lever mechanism 29 30 33 for actuating the shaft are all brought to a stop when the arm 22 strikes the actuated or depressed key or stop-piece. This stop-arm 22, mounted directly on the shaft 21, thus positions the segment and also positively stops or arrests the lever mechanism 29 30 33, while the hammer, loosely connected to or engaged by the lever 11, will continue its motion by its momentum 40 after the stoppage of the lever mechanism, so as to give the printing stroke.
- 45 By having the stop-pieces 23 extend upwardly and the arm 22 located above keys 15 the arm 22 is in reach of the operator and allows the type-wheel to be turned or held to one side or another—for example, when brushing or cleaning the type. To engage the upwardly-extended pieces 23, the guide 25 is located above the key-levers 15.
- 50 It is noted that the stop-arm 22 is secured directly to shaft 21, on which the type-segment 7 is mounted. By this construction gear or other intermediate connections between shaft 21 and arm 22 are avoided, which gears are objectionable, as adding to the parts of the machine, and also because such gears have been found to permit a certain degree of looseness

or vibration, which may cause a blur or a split print or letter.

The hammer 8, as seen, is a rigid arm swinging loosely on its pivot 9 and normally resting by its weight directly on lever-arm 11. As soon as this lever is thrown upward the hammer is thrown toward the type. By having the hammer rest directly on and actuated directly by 70 the lever 11 a simple structure is obtained, which avoids the necessity of any driving-spring for the hammer, and such structure is strong and durable and not liable to weaken, as might occur where a spring is employed, especially if such spring has to be kept permanently under more or less tension. As the hammer and lever 11 are both rigid or non-yielding and as the hammer rests positively or non-yieldingly on the lever 11, the full force 75 of the upward throw of the lever is imparted directly to the hammer. The lever-arm 11, as seen, is also of considerable length, and the point 10, where the arm 11 engages hammer 8, is located back of the carriage. This arm 11, 80 because of its length, is capable of a considerable sweep or swing to readily impart the required force to the hammer for giving an effective printing stroke.

What I claim as new, and desire to secure 95 by Letters Patent, is—

1. A type-writing machine provided with a type-segment and shaft, key-levers extended from the rear of the machine forward, a stop-arm on the shaft, and upwardly-extending stop-pieces on the top edges of the keys intermediate their front and rear ends, substantially as described.

2. A type-writing machine provided with a type-segment and shaft, key-levers for actuating the shaft, and a stop-arm on the shaft, said keys having their top faces provided with upwardly-projecting stop-pieces for arresting the arm substantially as described.

3. A type-writing machine provided with a type-segment and shaft, key-levers for actuating the shaft, and a stop-arm on the shaft, said keys having stop-pieces for arresting the arm, and said stop-pieces being cut or receding to allow the arm to pass when the keys 115 are at rest substantially as described.

4. A type-writing machine provided with a type-segment and shaft, a stop-arm on the shaft, key-levers provided with upwardly-extending stop-pieces for arresting the arm, and a guide for the stop-pieces located clear of or out of contact with the key-levers substantially as described.

5. A type-writing machine having key-levers provided with stop-pieces, a plate or 125 guide for the stop-pieces, and a type stop-arm made to travel between the plate and the levers, said stop-pieces having a cut or recess portion for the passage of the arm when the levers are at rest substantially as described.

6. A type-writing machine having key-levers, stop-pieces made to extend upwardly from the key-levers and comprising a stop portion and a passage portion or cut, a plate

- or guide for the stop-pieces above the levers, and a type stop-arm made to travel between the plate and levers, said cut being formed at the lower part of the stop-pieces or at the lever, and said lever being made to normally hold the stop-piece up or to the plate with the cut in the stop-piece in position for the passage or travel of the stop-arm substantially as described.
10. 7. A type-writing machine provided with a type-segment and shaft, key-levers for actuating the shaft, and a stop-arm fixed directly to the shaft, said keys having stop-pieces for arresting the arm and said type-segment being mounted on said shaft substantially as described.
15. 8. A type-writing machine provided with a hammer and an actuating-lever therefor, and a stop for arresting the lever short of the printing-point or position of the hammer, said lever and hammer being both rigid or unyielding and said hammer being made to normally drop or rest by its weight directly on the lever substantially as described.
20. 9. A type-writing machine provided with a type-segment and stop, a key-lever, an actuating-lever for the type-segment, a hammer, and an actuating-lever for the hammer, said hammer and segment-actuating lever being actuated by the key-lever and said stop being arranged to be arrested by said key-lever for arresting the hammer and segment-actuating lever short of the printing-point or position of the hammer and said lever and hammer being both rigid or unyielding and said hammer being made to normally drop or rest by its weight directly on the lever substantially as described.
25. 10. A type-writing machine provided with a type-segment shaft having a stop-arm positively or directly secured thereto, a hammer, key-levers, and levers for transmitting motion from the key-levers to the hammer and shaft, said stop being made to contact with the key-levers for arresting the shaft and transmission-levers short of the printing-point or position of the hammer and said lever and
- hammer being both rigid or unyielding and said hammer being made to normally drop or rest by its weight directly on the lever substantially as described.
30. 11. A type-writing machine provided with a type-segment shaft, a key and lever mechanism for actuating the shaft, a stop on the shaft for positioning the segment and arresting the lever mechanism, and a hammer loosely connected to the lever mechanism to continue moving by its momentum after the stoppage of the lever mechanism so as to give the printing stroke and said lever and hammer being both rigid or unyielding and said hammer being made to normally drop or rest by its weight directly on the lever substantially as described.
35. 12. A type-writing machine provided with a type-segment shaft having a stop-arm mounted directly on the shaft, a hammer, key-levers, stop-pieces secured to or operated directly by the key-levers, and levers for transmitting motion from the key-levers to the hammer and shaft, said stop-arm being made to contact with or be positively arrested by the stop-pieces and said lever and hammer being both rigid or unyielding and said hammer being made to normally drop or rest by its weight directly on the lever substantially as described.
40. 13. A type-writing machine provided with a type-segment shaft having a stop-arm, a hammer, key-levers, stop-pieces made to form part of the key-levers and to directly arrest the stop-arm, and levers for actuating the hammer and shaft, said stop-pieces and arm being located above the key-levers and said arm being fixed directly to the segment-shaft substantially as described.

In testimony whereof I have hereunto set my hand in the presence of two subscribing witnesses.

WILLIAM P. QUENTELL.
